[57] CLAIM

The ornamental design for an infant seat, substantially as shown.

DESCRIPTION

FIG. 1 is a front perspective view of an infant seat
showing my design;

FIG. 2 is a rear perspective view;

FIG. 3 is a side elevational view of the infant seat of
FIG. 1 but shown in an alternate position; and

FIG. 4 is a bottom plan view thereof.
